UNITED STATES PATENT OFFICE.

ALICK G. RICHARDSON, OF ROCHESTER, AND WILLIAM J. ATWOOD, OF NEW YORK,
N. Y., ASSIGNORS TO RICHARDSON CORPORATION, OF ROCHESTER, NEW YORK, A
CORPORATION OF NEW YORK.

DESIGN FOR A DISPENSING-COOLER FOR BEVERAGES.

57,095.

Specification for Design.

Patented Feb. 8, 1921.

Application filed May 7, 1920. Serial No. 379,681. Term of patent 14 years.

To all whom it may concern:

Be it known that we, ALICK G. RICHARDSON and WILLIAM J. ATWOOD, of Rochester, in the county of Monroe and State of New York, and borough of Manhattan, city, county, and State of New York, respectively, have invented a new, original, and ornamental Design for a Dispensing-Cooler for Beverages, of which the following is a speci-

fication, reference being had to the accompanying drawing, forming a part thereof.

Figure 1 is a front view, and

Fig. 2 is a side view.

We claim:

The ornamental design for a dispensing cooler for beverages, as shown.

ALICK G. RICHARDSON.
WILLIAM J. ATWOOD.
